UNITED STATES PATENT OFFICE.

DANIEL C. MULVIHILL, OF HANNIBAL, MISSOURI.

METHOD OF MOLDING AND FLASK PART THEREFOR.

1,414,702.

Specification of Letters Patent. Patented May 2, 1922.

Application filed June 23, 1919. Serial No. 306,049.

To all whom it may concern:

Be it known that I, DANIEL C. MULVIHILL, a citizen of the United States, and resident of Hannibal, county of Marion, 5 and State of Missouri, have invented certain new and useful Improvements in Methods of Molding and Flask Parts Therefor, of which the following is a specification, and which are illustrated in the 10 accompanying drawings, forming a part thereof.

An object of the invention is the provision of a method of molding, wherein the entire compacting or condensing of the sand is secured on the jolting machine without the 15 addition of any weighting substance aside from the sand forming part of the finished mold.

A further object of the invention is the 20 provision of a flask part of such a nature that the process referred to may be successfully carried out.

The structure embodying the invention, shown as different forms of copes capable 25 of carrying out the process, is illustrated in the accompanying drawings, in which

Fig. 1 is a plan view and

Fig. 2 is a section on the line 2—2 of 30 Fig. 1, of a cope in place on a pattern, the whole supported on a stripping plate and jolting table;

Fig. 3 is a vertical section on the line 3—3 of Fig. 1;

Fig. 4 is a plan view of a modification; 35 Fig. 5 is a vertical section on the line 5—5 of Fig. 4; and

Fig. 6 is a partial plan view of another modification.

The structure which has been chosen to 40 illustrate a physical embodiment of the invention is a cope for use in casting car wheels.

As illustrated the cope comprises an exterior rim 10, and is provided with a chill 45 11, shown in Fig. 2 as supported on a pattern 12 and stripping ring 13, the ring and chill being provided with steady pins, as 14. The stripping ring and pattern are shown as supported on a stripping plate 50 15, the ring and plate being described and claimed in application Serial No. 306,050 filed of even date herewith. The above-referred to parts are shown as lying upon the table 16 of a jolting machine of any 55 known type.

The interior of a cope of the type illustrated is so great in area as compared with its depth that, if undivided, the mass of sand therein could not be compacted sufficiently to prevent "drops" when lifting 60 the flask part from the pattern. To obviate this it has been common to subdivide this space by means of bars or partitions, as 17. In the past a maximum of fifteen bars has been used, and whether this exact number 65 has been used or not they have in all cases been spaced apart a greater distance than the height of the bars.

The present invention depends upon the discovery that if the bars be placed sufficiently near together the action of the jolting machine alone, without hand ramming, repressing, or the use of a weighting material on the sand while being treated by the jolting machine, will compact the sand 70 75 so that the flask part and the compacted sand may be stripped from the pattern and lifted successfully.

As the result of experiment it is found that if the width of the spaces between the 80 bars does not exceed their height the above referred process of compaction by jolting alone may be successfully carried out with, however, an occasional failure. It is preferred, however, to so space the bars that 85 their height shall considerably exceed the greatest distance between them, and to this end twenty-seven bars, 17, are shown in Fig. 1 of the drawing. With spaces resulting from the use of this number of bars 90 it is found that by employment of the jolting machine alone the sand is rendered more dense than when jolted and hand rammed or repressed in the usual manner, and, moreover, that the density of the 95 sand is substantially uniform throughout the mass instead of having a shell on the surface, as results to some extent from previous practice.

To connect and support the inner end 100 of the bars an interior ring 18, shown as concentric with rim 10, is provided.

It is found that the process is carried out with more complete success when the bars and also the interior ring are tapered uniformly from the upper edge to the lower edge. In practice the lower edges are preferably reduced to substantially one-eighth of an inch.

For subdivision of the space in the in- 110

terior of ring 18, stub bars, as 19, may be provided preferably cast integral with the ring, and, as shown, are also tapered from above downwardly. A gate forming implement is shown at 20, Fig. 1, and is more fully illustrated and described in the co-pending application above referred to, the same forming no part of the present invention.

10 In order that the ends of the stub bars 19 may be substantially parallel with the flaring dish portion 21 of implement 20, said ends are preferably cut away at their upper portions, as shown at 22, Figs. 2 and 5.

15 The form of cope shown in Figs. 1 and 2 has a desirable spacing of bars at their outer ends, but are unnecessarily close together at their inner ends. Forms of the invention are shown in Figs. 4 and 6, where-
20 in the bars are not so closely spaced near the center and are still sufficiently close at the circumference. In the form of Fig. 6 stub bars, as 23, attached to the rim 10 are placed between bars 17 to subdivide the spaces between bars 17 at the widest portion. This form of the invention introduces a weakness of construction in that the stub bars are liable to breakage. This weakness is avoided by the form of Fig. 4, in which
25 a supplemental interior ring 24 is shown, which ring in effect spans the space between the bars 17 of Fig. 6 and is connected to the end of stub bars 23 by being cast integral therewith.

30 The cope illustrated is preferably constructed of cast iron. It is found that when a cope constructed as disclosed is placed with the pattern on a jolting machine and filled with sand and jolted substantially the usual
35 number of times, the sand will be compacted as explained above, and that drops substantially never occur, and, moreover, that the sand need not be more than ordinarily moist to successfully carry out the process.

I claim as my invention—

1. A flask part for molding car wheels, comprising bars dividing the sand space of the cope into compartments whose depth is substantially greater than the greatest distance between the bars measured in a plane 50 perpendicular to a radius bisecting one of said compartments.

2. A cope for molding car wheels, comprising an external rim, and downwardly tapering bars within the rim dividing the 55 sand space into portions whose depth is substantially greater than the greatest distance between the bars measured in a plane perpendicular to a radius bisecting one of said portions.

3. A cope comprising an external circular rim, an interior ring concentric therewith, radially disposed bars attached at their ends to said rings, the greatest separation of said bars being substantially less than their 65 depth, the separation being measured in a plane perpendicular to a radius bisecting the space between two of said bars.

4. A cope comprising an external circular rim, an interior ring concentric with the 70 outer rim, radially disposed bars attached at their ends to said rings, the height of said bars being substantially greater than the spaces between the bars measured in any plane perpendicular to a radius bisecting the 75 space, and stub bars each attached at one end to said interior ring and extending inwardly therefrom.

5. The method of molding car wheels which comprises providing a circular flask 80 part, the space within which is divided by radially extending partitions, the maximum spacing of which is less than the least height of the partitions, placing sand in the flask part on a pattern, and compacting the sand 85 by jolting only and without application of other compacting means.

DANIEL C. MULVIHILL.
